UNITED STATES PATENT OFFICE.

THEOPHILE BACKELJAU, OF MALINES, BELGIUM.

AUTOMATIC GAS-MOTOR.

SPECIFICATION forming part of Letters Patent No. 364,205, dated June 7, 1887.

Application filed November 15, 1884. Serial No. 147,986. (No model.) Patented in Belgium August 2, 1884, No. 65,933; in Germany August 13, 1884, No. 35,102, and in England August 16, 1884, No. 11,361.

To all whom it may concern:

Be it known that I, THEOPHILE BACKELJAU, a subject of His Majesty the King of the Belgians, residing at Malines, in said Kingdom of Belgium, have invented certain new and useful Improvements in and connected with Automatic Gas-Motors, of which the following is a specification.

This invention relates to an automatic motor operated by the successive explosions of gas or of solid or liquid combustible or explosive substances pulverized or vaporized, and by the vacuum which follows these explosions. The explosive force acts directly on the working parts without the use of any intermediate mechanism.

To clearly explain my invention so that others skilled in the art may practice the same, reference is made to the accompanying drawings, which form part of this specification, and in which—

Figure 1 represents in sectional elevation a mixer such as hereinafter more fully described. Fig. 2 represents in sectional elevation an explosion-chamber in which is the igniter and the means for applying the force generated by the explosion to a force-pump. Fig. 3 represents in side elevation a rotary motor as driven in accordance with my invention. Fig. 4 represents in sectional elevation a piston and cylinder driven in accordance with my invention, while Fig. 5 represents the motor applied to a large-size marine or other engine. Fig. 6 represents a detail view in section of the relative arrangement of the mixing and igniting chambers.

The apparatus comprises, first, an arrangement for receiving the chosen combustible or explosive substance, whatever it may be, and the substance for supporting the combustion, (such as oxygen or air;) second, a mixer, in which the two substances are mixed together in suitable proportions, according to requirements; third, an igniter operating automatically and determining the explosions.

For the explosive gases I preferably employ illuminating-gas and air carbureted by combustible or explosive liquids. In order to produce powerful effects, it is preferable to employ liquid itself injected in the form of spray and vaporized at each explosion.

For the purpose of utilizing petroleum (or other common substances) I employ a special carburetor—not shown in the drawings, but which will be readily understood from the following description: The bottom of this carburetor is filled with petroleum. The vessel itself is provided centrally with a tube open at both ends and perforated with holes at its upper part. At the center of this tube, and supported on the reservoir, is placed a small burner fed from the reservoir.

Around the central tube, and in contact with it, are grouped a suitable number of tubes of a lesser diameter, containing wicks which dip into the petroleum. The whole is surmounted by a funnel terminating at a pipe in communication with the before-mentioned mixer. When the central burner is ignited, the heat it disengages is communicated to the small tubes by means of the central tube, and as large a quantity of gas as may be desired can thus be produced. The gas is conducted through a tube, *a*, regulated by a cock, *b*, into the mixer *A*, and beneath the surface of a liquid, *C*, placed therein, such liquid acting as a hydraulic valve. The gas passes up through the liquid *C* and meets a regulated quantity of air, which is supplied through a second pipe governed by a cock or tap, *e*, by the adjustment of which the proportions of the explosive mixture are determined. In the pipe *d* of the mixing-chamber a two-way valve, *o*, is mounted, which is adapted to regulate the flow of gas through the said pipe, or through the branches *n n*, which also connect therewith on each side thereof, and which may be provided with screw-tapped ends to engage with suitable conducting-pipes.

The igniter consists of a spiral platinum wire, *f*, fixed at the end of a small copper tube, *g*. The orifice of said tube which is nearest to the igniter is almost closed by platinum gauze. The igniter may be placed either on the cylinder-cover or in any other suitable position.

The igniting-chamber consists, essentially, of a metallic cylinder or box, *B*, which has two pipes, *g h*, provided with valves *j k*, said pipes entering and connecting with the top portion of the cylinder *B* separate and apart from each other. The pipe *h* is connected with the top portion of the pipe *d* of the mixing-chamber

A, as shown in Fig. 6, while the pipe *g* is connected to one of the branches *n* thereof. A suitable copper tube is attached or formed with the lower portion of the pipe *g*, which 5 protrudes into the chamber B, and to which the platinum spiral *f* is secured, said pipe *g* being arranged adjacent to an opening, *i*, in the side of the cylinder B, which is adapted to be opened or closed, as desired, by means of a 10 suitable valve. By the construction of the valve *o* as described the quantity of gas which flows into the explosion-chamber may be regulated as desired, independent of the valves *j k*, which may be automatically-operating valves 15 adapted to be opened or closed by the explosion in the chamber B. This chamber B and mixing-chamber A are used together in varied forms in all of the applications of the motor without materially departing from the construction described.

In order that the working of the apparatus may be readily understood, I will describe it as applied to a suction and force pump, said pump being arranged as follows, reference being made to Fig. 2:

The upper portion of the cylinder B is adapted to receive the explosive gas, while the lower or connected part, C, is provided with a branch pipe, E, which in turn is connected 30 with the suction-pipe L. The lower part, E, is provided with a one-way valve, *l*, beyond which is fixed an air-vessel, D, into which is passed the end of a force-pipe, G, terminating in a check or retaining valve, *m*. The cover 35 of the cylinder B is perforated with two openings, the igniter *f* and pipe *g* being fixed in one and the explosive-gas-supply tube *h* in the other, said pipes being governed by cocks *k j*. Upon leaving the before-described mixer 40 the explosive gas is forced into the cylinder through the tube *h*.

Beneath the igniter a small aperture, *i*, is provided, which serves for the initial ignition of the igniter. To put the apparatus in operation, the main gas-supply pipe *h* is closed, and only a small quantity of gas is forced in 45 through the platinum gauze at the end of tube *g* by means of a blower, or of the small pump fixed to the cylinder, the aperture *i* beneath the igniter is opened and a light is applied to 50 the igniter. The flame thus produced renders said igniter incandescent. This having been accomplished, the aperture *i* is closed and the main gas-cock *j* is opened, permitting the gas 55 to pass into the cylinder B. The velocity of the gas will at first cause the igniter to blacken, but as soon as the velocity diminishes it becomes revivified to incandescence and inflames and explodes the gas introduced into the cylinder. The vacuum which follows this 60 explosion causes the water to flow in from the water-supply pipe L, and at the same time a fresh charge of gas through tube *h*, which is in turn exploded, and the operation thus becomes automatic. After each detonation the 65 products of combustion are expelled simultaneously with the water through the dis-

charge-valve *l*. The water compresses the air contained in the air-vessel D, and also raises the valve *m* in the force-pipe G, through which 70 a portion of the water is discharged, while between the detonations the air contained in the air-vessel D expands and drives a further quantity of water out through the said force-pipe G.

It will be evident that if the explosive gas is supplied at sufficient pressure the continuous blower, or the air-pump, as shown at P, Fig. 5, and before referred to as necessary for starting the apparatus, will not be requisite.

In order to prevent the heating of the cylinder B and to obtain a continuous working, the cylinder may be inclosed within a second concentric cylinder, the space between said cylinders being filled with water supplied by 85 the apparatus, said space being supplied with suitable inlet and exhaust pipes.

According to my invention the following advantages may be obtained:

First. The introduction of the gases into a 90 cylinder without immediately exploding them, notwithstanding the contact and presence of the platinum igniter in a state of incandescence.

Second. Effecting the incandescence of the 95 platinum, and, as a consequence, the ignition of the gases by varying means—that is to say, by augmenting or diminishing the speed of the gases at the outlet on the igniting focus according to the arrangement of these foci, 100 and by varying the mixture of the explosive substance supplied.

Third. The direct application of the force resulting from the expansion of the gases within a closed space to nearly all machines, 105 among which may be specially named piston or rotary motors, suction, force, and fire-engine pumps, marine engines or boat propellers, vacuum apparatus and compressors, forging-hammers, stamping-mills, rock-cutters, 110 perforators, and the like. For example, in Fig. 3 a rotary motor is shown fitted with pinions. The pressure from the explosion-cylinder passes into and through chamber H, and the gases finding an outlet through the 115 valve at *n*, the vacuum produced causes air to pass in through pipe *o* and valve *p*. Thus a continuous regular motion and a powerful motor of small size are obtained, physically working without any mechanical distributing 120 motion.

Fig. 4 represents an arrangement of piston-motor, but more especially the adaptation of gas-power to percussion-tools. I is the explosion-chamber, the explosion in which causes 125 the piston J to move, and when it has arrived at the end of its stroke, as indicated by dotted lines, the products of combustion exhaust through parts *q* into a casing, *r*, and, after raising a valve, *s*, pass out through the chimney 130 K. The piston speed is regulated simply by the velocity at which the gases are introduced into the explosion-chamber I.

Fig. 5 represents the application of my mo-

tor to an engine for propelling a boat. The explosion of the gases takes place in the cylinder B, water is drawn in through L, and is forced out through M upon the opening of a 5 valve fixed in N.

The apparatus hereinabove described constitutes a novel means for the production of power, which is characterized by the collective parts forming a transportable whole, its 10 advantages being simplicity, cheapness, and economy in its working.

What I claim as my invention, and desire to secure by Letters Patent, is—

1. In a gas-engine, the combination, with a 15 mixing-chamber having independent inlets

for gas and air and a single outlet, of a separate igniting-chamber containing a metallic igniter adapted to be heated to incandescence by each successive supply of gas, and thereby to explode the same, substantially as described. 20

2. The combination, with the mixing-chamber, the igniting-chamber, a connecting-pipe, and a metallic igniter, of the opening *i* in the igniting-chamber, substantially as described, and for the purposes set forth.

THEOPHILE BACKELJAU.
